Specification of Letters Patent.

Patented Dec. 1, 1914.

Application filed April 18, 1914. Serial No. 832,730.

To all whom it may concern:

Be it known that I, DAVID T. WILLIAMS, a subject of the King of England, residing at Paterson, in the county of Passaic and State of New Jersey, have invented certain new and useful Improvements in Automatic Stokers, of which the following is a specification.

This invention relates to stoking equipment for locomotives.

One of the objects of the invention is to construct the two portions of that type of stoking equipment which comprises a forward and an after portion so related to each other that the after portion discharges into an upwardly open hopper or receiver forming a part of the forward portion and from which receiver the fuel is suitably advanced to the fire so that the discharge from the after portion shall be distributed instead of always at one place in the receiver, whereby the means which advances the fuel from the receiver to the fire may operate with increased efficiency.

Another object of the invention is so to construct and arrange the parts of a stoker equipment employing screw means to advance the fuel forwardly to the fire as to bring about increased efficiency and make it unnecessary to provide the gearing or the like whereby said means is driven with means to prevent the same from becoming clogged with particles of the fuel escaping from the means through which the fuel is advanced.

The invention will be found fully illustrated in the accompanying drawings, wherein,

Figure 1 is a longitudinal sectional view of the improved equipment in place on a locomotive and its tender; Fig. 2 is a plan of the essential parts of the equipment, the tender appearing in horizontal section; Figs. 3, 4 and 5 are transverse sectional views on lines $x-x$, $y-y$ and $z-z$ of Fig. 1; and, Fig. 6 illustrates a detail.

The locomotive a having the fire-box b and the rearwardly projecting frame structure c is of usual construction. The tender d has the bottom of its fuel bunker e formed as walls f which incline from the sides of the tender, being supported at their inner edges by the angle irons g secured along the upper edges of spaced vertical walls h extending longitudinally of the tender and

connected by a horizontal wall i which forms therewith an elongated space or channel j . The channel j is covered from the walls f forwardly by the fixed plate k forming the deck of the tender, but between the walls f it is open, excepting for the cover plates l which are placed in partly covering relation to the channel when the bunker is first filled, being successively removed or shifted as the body of fuel in the bunker is reduced until all of the fuel has been withdrawn from the bunker.

The structure c supports the means for receiving the fuel from the tender to be thereupon advanced to the fire. This includes in the present instance a passaged structure m whose forward tubular portion m' projects upwardly through the grate n of the locomotive and which at the rear is provided with an upwardly open receiver o having a wide mouth and in transverse section appearing substantially V-shaped (Fig. 5). Also included in the said means are a rotary horizontal screw p and a rotary vertical screw q ; the shaft p' of the screw p , which is arranged in the receiver o , has its rear end protruding through and suitably journaled in the rear wall o' of said receiver and its forward end journaled in a bracket o'' arranged in the forward or open end of the receiver, while the shaft q' of the screw q , which is arranged vertically in the part m' of the passaged structure, has its lower end suitably journaled in and protruding through the bottom of said structure.

s is a suitably driven rotary shaft journaled in brackets depending from the receiver o (Fig. 5) and carrying a worm s' which meshes with a worm-wheel s^2 arranged fixed on the protruding end of the shaft p' . Said end of said shaft carries a gear s^3 which meshes with a gear s^4 on the shaft s^5 arranged parallel with and below the screw p and journaled in the draw-head s^6 of the locomotive and carrying at its forward end bevel gear s^7 meshing with a bevel gear s^8 on the shaft q' . Means is thus provided for driving the two screws which is efficient in character and which includes power-applying and transmitting means that is entirely exterior of the structure m , so that special provision of means to prevent the gearing involved from becoming clogged with particles of the fuel escaping from said structure is unnecessary. In the channel j

slides longitudinally an upwardly open trough *t* somewhat wider than the space between the adjoining edges of the angle irons *g*, the said trough being adapted to be reciprocated in the channel and extending sufficiently far forward so that its forward end overhangs in any position thereof the receiver *o*. Preferably this trough is provided with flanged rollers *u* running on the rails *v* arranged at the bottom of the channel *j*; it may be reciprocated by the engine *w* shown in Fig. 1, with whose piston it is suitably connected by a crank *w'*.

When the apparatus is in operation, the fuel of course finds its way from the bunker into the trough, and on each forward movement of the trough the part of the fuel therein is bodily carried forward thereby. To check the rearward movement of the fuel in the trough as the latter moves rearwardly, whereby to accomplish the delivery of the fuel from the front end of the trough into the receiver, I provide a checking means preferably consisting of series of fuel checks *x*, each series being pivotally suspended from a shaft *y* (supported in the walls *h*) and depending into the trough *t*. Each check is free to swing forward on its axis to a substantially horizontal position, but it is limited against swinging rearwardly past the vertical by a lug *z* thereon coming in contact with a suitable stop-bar *2*. In the detail shown in Fig. 6, the shaft *y* and bar *2* are each supported at each end by a bracket *3* bolted to the angle iron *g*.

The operation of the mechanism will be obvious in view of the foregoing: On each forward movement of the trough the checks *x* yield forwardly to the advancing fuel therein; on each rearward movement the checks come to a stop against the bars *2* so that, as the trough continues to recede, the body of fuel therein is delivered therefrom at its forward end into the receiver. The manner of the delivery is such, due to the

coincident rearward movement of the trough, that the fuel is distributed along the length, more or less, of the screw *p* (kept constantly rotating by the means described), instead of continuously at one point. 50

It will be understood on reference to Fig. 5 that the relative widths of the trough and receiver *o* are such that the trough in swinging laterally will always overhang the receiver. 55

Having thus fully described my invention, what I claim as new and desire to secure by Letters Patent is:—

1. In combination, with a locomotive-and-tender system including a locomotive fire-box, a tender-bunker, a receiver and means to advance the fuel from the receiver to the fire-box, means to advance the fuel from the bunker to the receiver comprising a longitudinally reciprocating trough having one end overhanging the receiver and a fuel check coöperative with the trough and relatively to which said trough reciprocates, said check being yieldable to the movement of the fuel past the same toward the said end of the trough. 60 65

2. In combination, with a locomotive-and-tender system including a locomotive fire-box, a tender-bunker, a receiver and means to advance the fuel from the receiver to the fire-box, means to advance the fuel from the bunker to the receiver comprising a longitudinally reciprocating trough having one end overhanging the receiver and a fuel check coöperative with the trough and relatively to which said trough reciprocates, said check being pivotally yieldable to the movement of the fuel past the same toward the said end of the trough. 75 80

In testimony whereof I affix my signature 85 in presence of two witnesses.

DAVID T. WILLIAMS.
